UNITED STATES PATENT OFFICE

2,050,029

HEAT TREATING APPARATUS

Thomas D. Williams, Cleveland, Ohio, assignor
to The American Steel and Wire Company of
New Jersey, a corporation of New Jersey

Application August 14, 1934, Serial No. 739,807

2 Claims. (Cl. 266—5)

This invention covers a heat treating apparatus which includes a separable heating bell and work-carrying base constructed to cooperatively form an enclosure when brought vertically together, one of the objects being to heat the work evenly throughout by means of this apparatus. Other objects may be inferred.

The apparatus is illustrated by the accompanying drawings, in which:

10 Figure 1 is a vertical cross-section.

Figure 2 is a horizontal cross-section taken from the line II—II in Figure 1.

More specifically, a bell 1 and base 2 are constructed to cooperatively form an enclosure when brought vertically together. Heating elements 3 and 4 are mounted in the bell.

20 The base 2 provides a raised, recessed portion 5 that is centrally positioned so as to extend up into the bell 1. The recess 6 is of annular shape, and at least one heating element 7 is mounted in it.

25 A liquid seal 8 is circumferentially carried by the base 2. As is customary, the work within the bell is enclosed by a sheet metal hood 9 which extends between the bell 1 and base 2 into the seal 8.

To protect the element 7 against falling matter, a sheet metal hood 10 is constructed to cover the base and extend into the seal 8. This 30 hood has a raised portion 11 fitting the portion 5 of the base 2. Annular corrugations 12 are formed in the top of the portion 11 for the purpose of preventing buckling, and the base 2 is constructed to permit expansion of the side wall 13 of the portion 11. This construction includes an annular recess 14 in the part of the base 2 which is adjacent its portion 5, whereby vertical movement of the side wall 13 is accommodated.

40 The base 2 is provided with vertical pipes 15 which pass completely through its raised portion 5. Other vertical pipes 16 are loosely arranged through the pipes 15 and project through the top of the raised portion 11 of the hood 9 in gas-tight connection therewith. This connection may be made by welding the projecting ends of the pipes 16 to the top of the portion 11 of the hood 9, as at 17.

45 A hearth casting 18 rests on top of the portion 11 of the hood 9 so as to be supported by the raised portion 5 of the base 2. This hearth casting is constructed so as not to unduly obstruct the ends of the pipes 16 and so as to support the work. As is usual, the hood 9 includes a depending portion 9a which ac-

commades the heating element 4, and the hearth casting 18 is provided with an annular socket 19 which engages the portion 9a of the hood when the latter drops because of the heat.

The apparatus here disclosed is usually used 5 to treat coiled steel strip, as indicated at 20, and all of the parts described are therefore of a generally circular shape.

Also, the strip is usually bathed in a non-oxidizing atmosphere, which may be introduced 10 through the pipes 16. These pipes are connected to pipes 21 through readily releasable couplings 22. The arrangement is such that one or more of the pipes will introduce the inert atmosphere while the others are functioning as outlets.

Heretofore the bases used with furnaces of the bell type have simply functioned to support the work. The heating elements 3 and 4 were depended upon to heat the strip evenly, 20 and were carefully arranged with this in mind. However, experience has proven that the strip cannot be heated evenly in this manner. The use of the apparatus disclosed provides for the even heating desired, and is therefore a decided 25 improvement.

It should be noted that the work is enclosed between two sheet metal hoods which both extend into the same liquid seal. There is thus absolutely no chance for any leakage to occur. 30 Furthermore, should it become necessary to service the element 7, the pipes 16 may be uncoupled from the pipes 21, and the hood 10 and the pipes 16 raised bodily from the base so that the element is exposed.

35 Although a specific example of the apparatus is disclosed in accordance with the patent statutes, it is not intended that the scope of the invention be limited thereby, except as defined by the following claims.

40 I claim:

1. Heat treating apparatus including a separable bell and base which are constructed to cooperatively form an enclosure when brought vertically together, heating elements mounted 45 in said bell, said base providing a raised, recessed portion that is centrally positioned so as to extend up into said bell, a heating element mounted in said recess, a liquid seal circumferentially carried by said base, a sheet metal 50 hood constructed to cover said base and extend into said seal, said hood having a raised portion fitting said recessed portion and in the top of which annular corrugations are formed, said base being constructed to permit expansion of the side 55

wall of said portion of said hood, vertical pipes removably arranged through said base and projecting through the top of the raised portion of said hood in gas-tight connection therewith, and 5 means on said base over said hood for supporting work within said bell.

2. Heat treating apparatus including a separable bell and base which are constructed to cooperatively form an enclosure when brought 10 vertically together, said base providing a raised,

recessed portion that is centrally positioned so as to extend up into said bell, a heating element mounted in said recess, and a sheet metal hood constructed to cover said base, said hood having a raised portion fitting said recessed portion and in the top of which annular corrugations are formed, said base being constructed to permit expansion of the side wall of said portion of said hood. 5

THOMAS D. WILLIAMS. 10
